UNITED STATES PATENT OFFICE.

WILLIAM E. CLOW, OF CHICAGO, ILLINOIS, ASSIGNOR TO JAMES B. CLOW & SONS, OF CHICAGO, ILLINOIS, A CORPORATION OF ILLINOIS.

CASTING MACHINE.

Application filed February 6, 1922. Serial No. 534,352.

The present invention relates to casting machines of that type in which molten metal is charged into a rotating mold and centrifugally cast against the interior surface of the mold. Its principal object is the provision of such a casting machine practically operable for the efficient and economical casting of hollow articles. The invention provides a machine especially adapted for the production of elongated articles such as pipe, by charging molten metal onto the rotating mold surface at longitudinally separated points and in such manner that the metal is directed onto the mold surface in the direction of rotation thereof and at an acute angle with relation to the mold surface. A preferred form of machine embodying the invention is illustrated in the drawings and explained in the following description.

In the drawings,—

Figure 1 is a broken vertical section of a machine embodying the invention.

Figure 2 is an end elevation thereof.

Figure 3 is a section on the line 3—3 in Figure 1.

Figure 4 is an enlarged section of the distributing trough on the line 4—4 in Figure 1.

The machine as a whole stands on a suitable concrete or other base 1. A plurality of suitable standards 2 are secured to the base and a casing 3 is rigidly and fixedly supported by the standards. The casing 3 is preferably constructed of cast iron. A mold 4, preferably made of forged steel, is rotatably mounted within the casing 3. The mold may be conveniently mounted within the casing by securing a pair of spaced roller bearings 5 in the casing adjacent the opposite ends thereof and supporting the mold on these bearings. A pulley 6 is secured to the mold at what may be called the rear end which projects beyond the casing and power may be suitably transmitted to the pulley to rotate the mold at high speed. Preferably, ball bearings 7 and labyrinth or other suitable packings 8 are provided between the mold and casing adjacent the opposite ends thereof. It is practically desirable to mount the ball bearings and packing at the rear end of the casing, so caged that they are incapable of movement with respect either to the mold or the casing. At the front end of the machine the bearing and packing are preferably secured in a cage

which is incapable of longitudinal movement with respect to the mold but which has a sliding fit within the casing to provide for movement due to expansion of the mold during operation. Both ends of the mold are open. At the rear end of the mold a flanged annular stop 9 is secured in the bore of the mold. The front end of the mold is enlarged and secured therein is a core 10 suitably shaped so that the bell end of a pipe will be cast between the opposing surfaces of the core and the enlarged bore of the mold. The body of the core 10 may be formed of metal or sand as desired and may be conveniently secured in place by having the mold project slightly beyond the front end of the casing and driving wedges through holes 11 formed in the projecting end of the mold.

A track 12 is supported on the base 1 and extends rearwardly from the rear end of the mold and casing. A carriage 13 is mounted on the track by providing the carriage with wheels 14 rolling on the upper surface of the track and with wheels 15 engaging the under surface of the track. A distributing trough 16 is rotatably supported by the carriage 13 and this is preferably accomplished by providing the carriage with spaced standards 17 housing suitable antifriction bearings 18 directly supporting the trough. A worm gear 19 is secured on the trough and meshes with a worm 20 journaled on the carriage and operable by a crank 21. Longitudinal movement of the carriage rearwardly from the mold withdraws the distributing trough 90 from the mold so that a cast pipe may be withdrawn from the front end of the mold and so that the trough when desired may be cleaned or repaired. Forward movement of the carriage projects the distributing trough 95 through the mold so that the front end of the trough projects beyond the front end of the mold and casing. The front end of the trough is preferably provided with a beveled surface 22 which strikes and rides the trough up on a roller 23 supported from the base. The roller 23 is carried by a bracket 24 pivoted on a vertical axis so that it may be swung out of the way after withdrawal of the trough to allow removal of the pipe from the mold. That portion of the distributing trough which is adapted to be projected into the mold is preferably formed by a cast steel shell 25 lined with fire brick or other refractory material 26. That portion of the 100 105 110

distributing trough which lies within the mold when the trough is projected into filling position is formed with a plurality of longitudinally separated discharge spouts 27 and preferably this portion of the trough is provided with an opening in its top and the spouts are formed in one edge of the opening. That portion of the trough which in filling position of the trough projects beyond the front end of the mold and the casing is formed with a filling opening 28. That edge 29 which corresponds with the edge in which the discharge spouts are formed extends to a higher level than the spouts. A transverse partition 30 is formed within the trough adjacent the rear end of that portion of the trough which lies within the mold. The casing 3 is provided with a water inlet 31 and a water outlet 32 connecting with the space between the casing and the mold so that cooling water may be freely circulated around the mold.

In operation, after the bell forming core has been secured in the front end of the mold, the carriage is advanced to project the distributing trough into operative position, in which it is illustrated in Figure 1. The mold is then rotated at high speed. Molten metal is charged in that portion of the trough projecting beyond the front of the mold and casing. As soon as the trough is filled with molten metal the worm gear is operated to rotate the trough and pour the metal into the rotating mold. The high edge of the filling opening on the discharge side of the trough prevents any metal from being spilled outside of the mold and as the trough empties the surplus metal in the projecting end of the trough will run back and be discharged near the front end of the mold to cast the bell end of the pipe. The discharge outlets or spouts in that portion of the distributor or trough positioned within the mold during the casting operation are so formed and disposed that as the molten metal is charged into the mold it will be directed onto the rotating mold surface in the direction of rotation thereof and at an acute angle with relation to the mold surface. The molten metal is thus delivered to the mold surface quietly and without agitation, so that it may be said to be "laid onto" the mold surface. In the preferred machine illustrated, the distributor is rotated so that the molten metal is delivered onto the mold surface gradually. The discharge spouts through which the molten metal flows from the trough into the mold are longitudinally separated so that the metal flows into the mold and onto the mold surface in streams which are spaced apart along the mold. Air and gas are permitted freely to escape inwardly from the mold surface toward the axis of the mold between the inflowing separated streams of metal, so that

before the adjacent streams of metal flowed into the mold have united the metal has inwardly displaced all air and gas. The trapping of air and gas between the metal and mold surface is wholly prevented and the resulting pipe will be devoid of pockets, blow holes and other imperfections. After the pipe has been cast the distributing trough is withdrawn, the guiding roller at the front of the mold is swung out of the way and the wedges holding the core in position are displaced, whereupon the pipe and core may be readily withdrawn from the front end of the mold and the core removed from the pipe.

Having thus described my invention, what I claim as new and desire to secure by Letters Patent of the United States is:

1. In a casting machine, the combination of an elongated rotary mold, and a distributor adapted to extend within the mold and provided with longitudinally separated discharge outlets adapted to direct molten metal onto the mold surface at an acute angle and in the direction of rotation thereof.

2. In a casting machine, the combination of an elongated rotary mold, and a rotatable distributor adapted to extend within the mold and provided with longitudinally separated discharge outlets.

3. In a casting machine, the combination of an elongated rotary mold, and a rotatable distributing trough adapted to extend within the mold, the trough being open at the top and provided along one edge of the opening with longitudinally separated discharge spouts.

4. In a casting machine, the combination of an elongated rotary mold, and a rotatable distributor adapted to extend within the mold and provided with longitudinally separated discharge outlets adapted to direct molten metal onto the mold surface at an acute angle and in the direction of rotation thereof.

5. In a casting machine, the combination of an elongated rotary mold, and a rotatable distributor adapted to extend within the mold and provided with longitudinally separated discharge outlets, the distributor being provided with a filling opening beyond one end of the mold.

6. In a casting machine, the combination of an elongated rotary mold, and a rotatable distributor adapted to extend within the mold and to project beyond one end thereof, the portion of the distributor within the mold being open at the top and provided along one edge of the opening with longitudinally separated discharge outlets, the projecting portion being provided with a filling opening, the edge thereof corresponding with said outlet edge being higher than the outlets.

7. In a casting machine, the combination

of an elongated rotary mold; a longitudinally movable carriage, and a distributor supported by the carriage and adapted to be projected within the mold, the distributor being provided with longitudinally separated discharge outlets adapted to direct molten metal onto the mold surface at an acute angle and in the direction of rotation thereof, and being provided with a filling opening beyond one end of the mold.

8. In a casting machine, the combination of an elongated rotary mold, a longitudinally movable carriage, and a distributor rotatably supported by the carriage and adapted to be projected within the mold, the distributor being provided with longitudinally separated discharge outlets.

9. In a casting machine, the combination of an elongated rotary mold, a longitudinally movable carriage, and a distributor rotatably supported by the carriage and adapted to be projected within the mold, the distributor being provided with longitudinally separated discharge outlets, and being provided with a filling opening beyond one end of the mold.

10. In a casting machine, the combination of an elongated rotary mold, a longitudinally movable carriage, a distributor rotatably supported by the carriage and adapted to be projected within the mold, the distributor being provided with longitudinally separated discharge outlets, and means for rotating the distributor gradually.

11. In a casting machine, the combination of an elongated rotary mold, a longitudinally movable carriage, a distributor rotatably supported by the carriage and adapted to be projected within the mold, the distributor being provided with longitudinally separated discharge outlets, and means for rotating the distributor gradually.

45

utor being open at the top and provided along one edge of the opening with longitudinally separated discharge outlets, and means for rotating the distributor gradually.

12. In a casting machine, the combination of an elongated rotary mold open at its ends, a longitudinally movable carriage mounted at one end of the mold, and a distributing trough rotatably supported by the carriage and adapted to extend through the mold and to project beyond the opposite end thereof, the portion of the trough within the mold being open at the top and provided along one edge of the opening with longitudinally separated discharge spouts, the projecting portion of the trough being provided with an opening in its top, the edge thereof corresponding with said spout edge being higher than the spouts.

50

55

13. In a casting machine, the combination of an elongated rotary mold open at its ends, a longitudinally movable carriage mounted at one end of the mold, a distributing trough rotatably supported by the carriage and adapted to extend through the mold and to project beyond the opposite end thereof, the portion of the trough within the mold being open at the top and provided along one edge of the opening with longitudinally separated discharge spouts, the projecting portion of the trough being provided with an opening in its top, the edge thereof corresponding with said spout edge being higher than the spouts, and means for rotating the trough gradually.
